THE ROSS MANUFACTURING COMPANY, OF CLEVELAND, OHIO, A CORPORATION OF
OHIO

ABRASIVE WHEEL TRUING DEVICE

Application filed September 17, 1928. Serial No. 306,592.

This invention relates to an abrasive wheel truing device in which greater rigidity of the device is obtained when used against an abrasive wheel and in which the hub bearings are carried in unitary structures which are removable and replaceable without adjustment of the bearings within the structures and in which the bearing structures are effectively sealed against admission of water, grit, and other foreign matter, and against the escape of oil.

An object of the invention is to provide an abrasive wheel truing device having a one piece axle.

Another object of the invention is to provide such a device with hub bearings assembled as unitary structures which are applied, removed or replaced as such unitary structures.

Another object of the invention is to provide a bearing structure which will lengthen the life of the bearings for such devices due to the fact that the inner or smaller bearing race is the one that revolves.

A still further object is to provide an effective water and oil seal for the bearings on an abrasive wheel dresser.

A yet further object is to provide a support for the hub of such a dresser arranged near the center of the same whereby the dresser may be held against an abrasive wheel with a greater degree of accuracy.

Another object of the invention is to provide an abrasive wheel dresser having unitary bearing structures which are effectively sealed against the admission and escape of liquid.

A still further object of the invention is to provide an abrasive wheel dresser with unitary bearing structures so constructed as to permit ready application and removal of the wheel of the dresser without the necessity of adjusting the bearings for every such removal and replacement.

Another object of the invention is to provide bearing structures for an abrasive wheel dresser in which the bearings are arranged in such manner as to prevent improper adjustment of the same when replacing the wheel of the device.

Another object of the invention is to provide an abrasive wheel dresser which is economical to manufacture, highly efficient in use and which permits ready substitution of the wheel.

It is finally an important object of this invention to provide a dresser device of the kind described wherein the rotary member is supported as a unit upon spaced bearings, the inner races of which rotate thereby assuming a relatively slow bearing speed, the supporting casing for said device being provided with a plurality of adjustable rests affording a support which absorbs torsional strain imposed on the device and relieves the shank of the tool from strain.

The above, other and further objects of the invention will be apparent from the following description, accompanying drawings and appended claims.

According to the invention, the device includes a closed unitary bearing structure for each end of the hub, which structures are sealed against admission of foreign matter and against escape of oil, together with an arrangement of bearing elements within such structures which prevents improper adjustment of the bearings every time an abrasive wheel is applied to the hub.

One form of the invention is illustrated in the accompanying drawings and the views thereof are as follows:

Figure 1 is a side elevational view of an abrasive wheel dresser embodying the invention.

Figure 2 is an enlarged vertical section on line II—II of Figure 1.

Figure 3 is a side elevation partially in section of the dresser.

The form of the invention illustrated in the accompanying drawings comprises a cast metal hood 1 having a member 2 integral therewith and a pair of spaced vertically movable rests 3 carried in apertured ears 4 and 5 on the sides of the hood. The rests 3 are threaded for a portion of their length, which threads cooperate with threads in the ears 5. By providing a pair of rests 3 and the member 2, a three point support is afforded which absorbs torsional strain and

relieves the shank of the tool from strain. The device is further self-adjusting.

The hood 1 is substantially semi-circular in elevation and has on each side thereof a semi-circular seat 6.

A strap 7 cooperates with the hood at each end thereof and is secured in position by bolts 8. The straps 7 and the circular seat 6 form pockets for the unitary bearing structures.

The form of the invention illustrated comprises a fixed bearing structure A and a removable bearing structure B which are secured in each side of the hood 1 in a manner above described.

A single axle or shaft 9 is supported in the bearing structures in a manner to be herein-after explained.

A hub 10 is mounted on the axle 9, which hub has an annular shoulder 11 against which the abrasive element 12 rest. The abrasive element 12 is secured against the shoulder 11 by a nut 13 locked in position by lock nuts 14. Suitable washers 15 are interposed between the abrasive element 12, shoulder 11 and the nut 13.

The shoulder 11 has projections 16 formed thereon for cooperation with a spanner wrench used when the abrasive element 12 is being fastened to or removed from the hub 10.

The fixed bearing A comprises a bearing cage 17 having a skirt 18 in the surface of which is formed an annular groove 19 opening radially outwardly.

The end of the hub adjacent the fixed bearing A is provided with an annular recess 20 opening axially into which extends the skirt 18 of the bearing cage 17.

A semi-floating sealing ring 31 of cork or other suitable sealing material is inserted in the recess or groove 19 of the skirt of the bearing ring 17 by being forced over the outside wall defining such groove. The depth of the groove provides for the compression of the cork ring between the bottom of the groove and the outer surface of the annular recess 20 in the hub. The ring 19 is compressed against the outside surface of the recess 20 in the hub when the parts are in assembled relation.

A thrust washer 21 is then placed on the axle 9 against the end of the hub 10.

An inner ball race 22 is then pressed on the axle against the thrust ring 21 and is locked to the axle by means of a lock washer 23 and a lock nut 24. The race 22, the washer 23 and the nut 24 are keyed or locked to the axle 9 by a key 25.

An outer ball race 26 is arranged within the bearing ring 17, which race has a sliding fit within the cage.

The outer ball race 26 is held in bearing alignment with respect to the inner ball race 22 by a retaining nut 27 which has threaded engagement with the bearing cage 17 and

which has an extension 28 against the outer ball race.

It will be observed that the fixed bearing A just described takes radial loads through the bearings and also thrust loads against the thrust ring 21 and the inner ball race 22.

The movable bearing structure B comprises a bearing cage or hood 28 having a skirt 29 provided with a recess 30 opening radially outwardly, carrying a cork sealing ring 31.

The end of the hub 10 adjacent the movable bearing structure B, has an outer annular recess 32 formed therein into which extends the skirt 29 of the bearing cage 28 and against the outer wall of which the cork sealing ring 31 has a compression fit.

A thrust ring 21 is applied over the end of the axle 9 at this end and against the end of the hub 10. The inner ball race 22 is pressed on the axle 9 against the thrust ring 21 and is retained in position on the axle 9 by a lock washer 23, lock nut 24, all of which are keyed by the key 25 to the axle.

The outer ball race 33 has a floating fit within the bearing carriage 28 and is axially movable with respect to the same. Bearing balls 34 are interposed between the inner and outer ball races of each of the bearing structures.

The outer ball race 33 of the movable bearing structure B is automatically self-aligning, that is when the parts are assembled as shown in the drawings, this outer ball race 33 will adjust itself to proper aligning bearing position with respect to its inner ball race 22.

The bearing structure B is closed at its outer end by an inclosure 35 in screw threaded engagement with the bearing cage 28.

It will be observed that the structure just described provides in a fixed bearing A a bearing arrangement which is adjusted in the unitary structure so as at all times to afford ample friction reducing cooperation between the hub 10 and the hood 1. The movable bearing structure B is the one which is removed and replaced whenever it is necessary to renew the abrasive wheel or element 12. The construction to the bearing structure B just described prevents any improper adjustment of the bearing within this structure, so that a careless or inexperienced operator cannot assemble the device in any but the proper way.

The device is used to true wheels by securing the member 2 in a suitable clamping device and resting the adjustable rests 3 on the shelf or tool rest of the machine. The members 3 may be adjusted vertically so as to bring the abrasive element 12 in proper relation with the wheel to be dressed so that the dresser will have proper support vertically on the shelf of the machine. Furthermore, the provision of the rests 3 with the member 2, a three point support for the abrasive element 12 near the axle or hub of the same is

secured, thus increasing the efficiency of the machine and making possible a better and more accurate dressing of the grinding wheel being treated.

5 The seal between the hub 10 and the bearing structures A and B is such as to prevent entrance of water, grit, or other foreign matter to the bearing structures and to prevent escape of oil from the bearing structures, thereby lengthening the life of these bearing structures.

The end closures 27 and 35 may be provided with oil holes 36 whereby lubricant may be supplied to the bearing structures.

15 We have found that the use of the cork sealing rings is efficient for the purpose intended, as these cork rings will outlast the ball bearings when properly treated before installation. The oil supplied to the bearing structures reaches the cork sealing rings, thus lubricating the same and lengthening the life of these sealing rings. The cork rings retain their resiliency for a long period of time in the arrangement hereabove described.

25 When it is desired to remove the abrasive element 12, the straps 7 are removed from the hood of the axle and its associated bearing structure and hub and are taken out bodily. The inclosure 35 is then unscrewed from the removable bearing structure B, the lock nut 24 is removed and also the lock washer, whereupon a bearing puller is screwed into the bearing cage 28 thus removing the bearing cage 28 as a unit. When this has been done, the lock nut 14 and the nut 13 are unscrewed from the nut 10 whereupon the used abrasive 12 may be removed and a new one applied.

35 Should it so happen that it is necessary to remove the fixed bearing structure A from the axle, such removal is accomplished as follows.

The inclosure 27 is unscrewed from the bearing cage 17, the lock nut 24, lock washer 23 are then removed and bars are inserted through axle holes 37 in the hub 10, which bars drive against the thrust washer 21 driving off the inner ball race 22.

40 It will be observed that such a device is efficient because of the rigid mountings of the bearings and the arrangement of the bearing elements against improper adjustment. Furthermore, the provision of the sealing rings and bearing cages exclude admission of grit, water, and other foreign matter from the bearing structures and at the same time confine the lubricating oil within the bearing structures.

45 While we have described more or less precisely the details of construction of our invention, yet we do not wish to be understood as limiting ourselves thereto as we are aware that changes may be made in the arrangement and proportion of parts and that equivalents may be substituted, all without de-

parting from the spirit and scope of our invention.

We claim as our invention:

1. An abrasive wheel truing device including a revolvable axle, a hub on said axle, bearing structures for each end of said hub, a stationary closure member for each end of said structures, and means for retaining each of said bearings in the same position of adjustment within said closures. 75

2. An abrasive wheel truing device including a revolvable axle, a hub on said axle, bearings for each end of said hub, a stationary closure member for each of said bearings, a side closure comprising a bearing cage 80 having an axle skirt with an annular groove in said skirt, the plane of which is perpendicular to the bearing axis, a cork ring within said groove inserted therein by being forced over a wall of said groove, said hub 85 having an annular recess the walls of which receive said cork ring and press the same in said groove to provide a seal between said hub and said bearing.

3. An abrasive wheel truing device including an axle, a hub on said axle, said hub having an annular recess in each end, a bearing structure for each end of said hub, a bearing structure comprising an imperforate bearing cage having a skirt projecting into 95 the hub recess adjacent its end, a sealing ring carried by said skirt and pressing against the outer wall of said recess, a thrust ring against the end of the hub, an inner ball race pressed against said ring and locked 100 to said axle, an outer ball race slidably mounted within said bearing cage, ball bearings between said races, and said outer ball race being axially movable for bearing adjustment with respect to said inner ball race. 105

4. An abrasive wheel truing device including a revolvable axle, a hub on said axle, said hub having an annular recess in each end, similar bearing structures for each end of said hub, a bearing structure comprising a 110 bearing cage having a skirt projecting into the hub recess at its end, said skirt having a groove therein opening readily outwardly, a cork ring within said groove having compressive engagement with the outer wall of 115 said recess for providing a seal between said hub and said bearing structure.

5. An abrasive wheel truing device comprising a head, an axle removably carried in said head, an abrasive wheel hub on said axle, bearing structures for said hub, one of said bearing structures being fixed with respect to said head and the other being movable, each of said structures comprising a bearing cage, a thrust ring against each end of said hub within the cage, an inner ball race pressed against said ring and locked to said axle, an outer ball race slidably within said bearing cage, ball bearings between said races, a sealing ring between each of said bearing cages 125 130

and its end of said hub, means associated with the fixed bearing structure for positioning the outer ball race in said structure in bearing alignment with its inner ball race, the outer ball race in said movable bearing structure being axially movable within its bearing cage for automatic bearing alignment with its inner ball race, and an end closure for each of said bearing structures.

10 6. An abrasive wheel truing device comprising a head, an axle removably carried in said head, an abrasive wheel hub on said axle, bearing structures for said hub, one of said bearing structures being fixed with respect

15 to said head and the other being movable, each of said structures comprising a bearing cage, a thrust ring against each end of said hub within the cage, an inner ball race pressed against said ring and locked to said axle, an

20 outer ball race slidable within said bearing cage, ball bearings between said races, a sealing ring between each of said bearing cages and its end of said hub, means associated with the fixed bearing structure for positioning the

25 outer ball race in said structure in bearing alignment with its inner ball race, the outer ball race in said movable bearing structure being axially movable within its bearing cage for automatic bearing alignment with its inner ball race, an end closure for each of said bearing structures, said hub having an axially

30 opening annular recess in each end thereof, each of said bearing cages having a skirt extending into the hub recess at its end of the hub, said skirts having radially opening

35 grooves therein, and cork rings in said grooves compressively engaging the outer walls of said hub recesses for providing a seal between said bearing structures and said hub.

40 7. An abrasive wheel dresser comprising a head, a revolvable axle removably carried by said head, a hub on said axle, said hub arranged for supporting an abrasive wheel for rotation therewith, unitary bearing structures carried by said head for supporting said hub, said bearing structures enclosing bearing elements, said bearing structures arranged to be applied and removed as a unit without affecting the adjustment of the bearing elements within said bearing structures.

45 8. An abrasive wheel truing device comprising an axle, a hub on said axle, bearings for each end of said hub, and a cork ring seal between each of said bearings and said hub, said ring being mounted compressed between opposed engaging surfaces.

50 9. An abrasive wheel truing device comprising an axle, a hub on said axle, bearings for each end of said hub, and a cork ring seal between each of said bearings and said hub, said ring being mounted compressed between opposed engaging surfaces, and being mounted for limited axial movement along said hub.

55 10. In an abrasive wheel truing device, in

combination, a revolvable axle, a hub secured on said axle, said hub having a longitudinally extending annular flange, a bearing for said axle, a hood on said bearing having a portion thereof projecting under said annular flange in spaced opposed relation thereto, and a cork ring seal seated compressed between said flange and said projecting portion of said hood to prevent dirt from entering said bearing.

In testimony whereof, we have hereunto subscribed our names at Cleveland, Cuyahoga County, Ohio.
